UNITED STATES PATENT OFFICE.

WILLIAM A. BREWER, OF PITTSBURGH, AND GUSTAVE A. GRUENDLING, OF NEW KENSINGTON, PENNSYLVANIA, ASSIGNORS TO P. H. MURPHY COMPANY, OF PAR-NASSUS, PENNSYLVANIA, A CORPORATION OF PENNSYLVANIA.

CAR-ROOF.

1,302,299.

Specification of Letters Patent. Patented Apr. 29, 1919.

Application filed December 20, 1918. Serial No. 267,585.

To all whom it may concern:

Be it known that we, WILLIAM A. BREWER, a citizen of the United States, and a resident of the city of Pittsburgh, county 5 of Allegheny, and State of Pennsylvania, and GUSTAVE A. GRUENDLING, a citizen of the United States, and a resident of the city of New Kensington, county of Westmoreland, and State of Pennsylvania, have 10 invented a new and useful Improvement in Car-Roofs, of which the following is a specification.

This invention relates to outside metal car roofs of the type wherein there are a 15 plurality of metal roof sheets movably mounted on the substructure and extending from eaves to ridge on opposite sides of the ridge and loosely connected along their side margins, and having their spaced ridge 20 margins movably connected by means of ridge caps.

One of the principal objects of the present invention is to hold the adjacent ridge corners of the roof sheets together without 25 the use of the four-way corner caps heretofore used for this purpose. Another object is to close the eaves ends of the side 30 seams and thereby eliminate the hood castings heretofore used for covering the open eaves ends of the side seams. Another object 35 is to improve the mounting of the end-most roof sheets so that these sheets will be free to shift on the car and accommodate themselves to any distortions of the car 40 substructure while in service. Other objects are to provide means for holding the adjacent ends of the ridge caps down on the car; to provide a weather-proof joint between the adjacent ends of the ridge caps 45 and the running board saddles; to provide a desired degree of rigidity for the overhanging portions of the end sheets; and to provide for ease in assembling the roof on the car.

The invention consists principally in improved means for movably securing the ridge corners of the roof sheets to the roof substructure; in making the side seams with hooded end portions; and in making the end 50 sheets with down-turned stiffening flanges at the outer side margins overhanging the car end. The invention further consists in the manner of securing the ends of the ridge

caps to the running board saddles and in the parts and combinations of parts herein- 55 after described and claimed.

In the accompanying drawings, which form part of this specification and wherein like numerals refer to like parts wherever they occur,

Figure 1 is a plan view of one end of 60 a car roof embodying our invention, parts being shown broken away to more clearly illustrate the invention;

Fig. 2 is a perspective view of the eaves 65 portion of one of the roof sheets showing the hooded side marginal flange which forms the outermost member of the interlocking side seams;

Fig. 3 is a perspective view of the eaves 70 portion of one of the roof sheets showing the side marginal flange which forms the innermost member of the interlocking side seams;

Fig. 4 is a transverse cross-section through 75 the ridge portion of the roof, the section being taken close to one of the running board saddles on the line 4-4 in Fig. 1;

Fig. 5 is a fragmentary longitudinal section through the end portion of the roof, 80 the section being taken close to one of the running board saddles on the line 5-5 in Fig. 1;

Fig. 6 is a longitudinal section taken 85 through the ridge portion of the roof at one of the running board saddles on the line 6-6 in Fig. 1;

Fig. 7 is a fragmentary plan view of the ridge portion of the roof, the running board 90 saddles and ridge seam covers being removed to disclose the four adjacent ridge corners of the roof sheets;

Fig. 8 is a cross-section through the eaves 95 portion of the roof, the section being taken close to one of the side seams on the line 8-8 in Fig. 1;

Fig. 9 is a perspective view of one of the corner clips;

Fig. 10 is a perspective view of the end 100 portion of one of the ridge caps;

Fig. 11 is a fragmentary perspective view of the eaves portion of one of the end sheets showing the doubled-under eaves portion and the down-turned outer side marginal portion which overhangs the car end; and 105

Fig. 12 is a longitudinal section through

the end portion of the car roof showing a form of clip for holding the end sheets down between the eaves and ridge.

The substructure of the roof shown in the drawing is of usual construction and comprises side and end sheathing 13 and 14, side and end fascia boards 15 and 16, and roof sheathing 17 which is supported at the eaves on side plates 18, at the end of the car on end plates 19 and at the ridge by means of a ridge pole 20. Metal roof sheets 21 extend from eaves to ridge on opposite sides of the ridge in alignment crosswise of the car, and are each provided at one side margin with an upstanding flange 22, which is re-bent inwardly and downwardly at its top over the body portion of the roof sheet. The opposite side margin of the roof sheet is provided with an upstanding flange 23, which is bent outwardly and downwardly from its top at an inclination, and then re-bent or hooked upwardly and inwardly for a short distance. By this arrangement, the inwardly bent flange 22 at one side margin of the sheet can be telescoped into the adjacent outwardly bent flange 23 of the adjacent side margin of the next sheet, thus forming an interlocking flexible seam connecting the side margins of the sheets. The lowermost or hooked portion of the outwardly bent flange 23 of one sheet clears the body portion of the adjacent sheet and is slightly lower than the lower edge of the inwardly bent flange 22 of the adjacent sheet, thus forming a neat sliding fit between these two interlocking flanges. The eaves end of the outer flange 23 of the side seams is provided with a hooded portion 24, which is open at the bottom and projects far enough beyond the eaves edge of the sheets to permit the escape of cinders, water or other matter which may enter the side seams. This hood portion also closes the end of the side seams and prevents water or cinders from blowing in the eaves ends of the seams.

The ridge margins of the sheets are provided with upstanding flanges 25, which are re-bent inwardly and downwardly from their tops over the body portions of the sheets in a manner similar to the side flange 22 of the sheets. The re-bent or inclined portions of the flanges 22, 23 and 25 are cut away for a short distance from the ridge corners of the roof sheets, but the up-standing or vertical portions of the flanges 22, 23 and 25 extend to the corners of the sheet, and the surplus metal at the corners is folded around as at 26, as shown and described in P. H. Murphy Patent No. 915,205 dated March 16, 1909. This arrangement produces solid corners and prevents any leakage at the corners of the sheets.

The eaves ends of the roof sheets are loosely held down on the roof substructure by means of a continuous angle flashing strip

27, which rests in a shallow rabbet formed in the eaves end of the roof sheathing below the ends of the roof sheets and is turned down over the side fascia 15 and nailed or otherwise secured in place. The inner margin 28 of the flashing strip 27 is bent back over the intermediate portion of the flashing strip and spaced far enough therefrom to accommodate the doubled-under flange 29 of the roof sheets, thus movably securing the sheet to the car substructure.

The sheets are held in position at the ridge by means of channel-shaped corner clips 30. These corner clips are located along the ridge line of the car between the ridge ends of the sheets and at the ridge corners thereof. The side walls of these clips are bent outwardly and downwardly at their tops to form inverted U-shaped flanges 31, which fit over the end portions of the ridge flanges 25 of the four adjacent sheets which corner on each other. The downwardly inclined portions of the U-shaped side flanges 31 of the corner clips 30 are curved upwardly midway between their ends, as at 32, to clear the ridge ends of the upstanding flanges 22 and 23 at the side margins of the roof sheets. The corner clips fit snugly over the side and ridge seams, thus holding the four sheets together at the corners.

The corner clips are held in position by means of vertical bolts 33, which pass through their center portions and are secured to the ridge pole. These bolts also secure the running board saddles 34, to which the running boards 35^a are nailed or otherwise secured. These running board saddles are provided on their under sides with V-shaped longitudinal grooves 36, which fit over the side seams of the roof sheets. These running board saddles are also channeled crosswise on their under sides at their middle to permit the saddles to straddle the corner clips 30 and the oppositely disposed ridge flanges 25 of the roof sheets. The space between the ridge ends of the sheets is covered by metal ridge caps 37 of semicircular section, which straddle the spaced ridge flanges of the roof sheets and are provided with foot flanges 37^a at each side which bear on the sheets on opposite sides of the ridge. These ridge caps are of less length than the distance between the side seams of the roof sheets and are provided with semicircular flanges 38 at each end, which fit into saw-cuts or slots 39 formed in the under side of the running board saddles.

The endmost sheets project a short distance beyond the end fascia 16 and their body portions are flanged downwardly, as at 40, and thence inwardly and upwardly at an inclination, as at 41, forming a stiffening flange along their outer side margins, which is spaced away far enough from the

end fascia to permit the end sheets to shift on the substructure and accommodate themselves to the distortions of the car frame. The doubled-under flange 29 at the eaves 5 end of the end sheets is also turned down over the end of the car with the flange 40 and thus forms a solid corner at the outside corner of the end sheets. The end of the endmost ridge cap is turned down, as at 42, 10 over the spaced ridge flanges 25 of the end sheets, and the end of the end ridge cap is held in position by means of a running board saddle 43, which is attached to the running boards 35 and straddles the end 15 ridge cap. Unlike the saddle 34, this saddle 43 is not secured to the roof substructure. With this arrangement, the end sheets are free from the car except at the eaves, where they are loosely held by eaves flashing, and 20 at the ridge, where the weight of the running board saddle 43 tends to hold the sheets and the end ridge cap in position on the car.

In the modification shown in Fig. 12, a 25 spring clip 44 is shown secured to the end fascia of the car. This clip extends upwardly at an inclinataion and has its upper end 45 hooked into the in-turned flange 41 of the end sheets and, if desired, may be used for holding the sheets down between 30 the eaves and ridge of the car.

By the arrangement described, the roof sheets are held together in their proper positions on the substructure by means of the corner clips 30, while their spaced ridge ends 35 are covered by the ridge caps, which, in turn, bear on the roof sheets and are held firmly in position by means of the running board saddles 34 and 43. This arrangement at the ridge of the car results in a water- 40 proof ridge construction and does away with the necessity for the four-way corner castings heretofore used for holding the sheets at the ridge. The hooded eaves ends of the side seams, which project out beyond the 45 end of the roof sheets, permit water and cinders that may accumulate in the side seams to flow out beneath the overhanging hooded portions, while these hooded portions also close the ends of the seams and prevent 50 water and cinders from blowing into the ends of the seams. This does away with the hood castings heretofore used for this purpose. The endmost sheets are free to shift on the car; and the turning down of their 55 outer side margins together with the doubled-under eaves portions greatly stiffens the overhanging outer edge and also prevents water from being blown under the ends of the sheets and entering the car.

60 The invention is not restricted to the precise forms and arrangements shown in the drawings.

What we claim is:

1. An outside metal car roof comprising 65 roof sheets extending from eaves to ridge on

opposite sides of the car, said roof sheets having upstanding flanges at their ridge margins and being movably connected along their side margins, ridge caps spanning the ridge margins of the oppositely disposed 70 roof sheets, clips located at the ridge of the car beneath said ridge caps, said clips resting on the roof substructure between the ridge margins of the roof sheets and having inverted U-shaped side marginal flanges 75 adapted to fit over the ridge corner portions of the upstanding flanges of the adjacent roof sheets for spacing and holding said sheets in position, and means for holding said ridge caps and said clips in position. 80

2. An outside metal car roof comprising roof sheets extending from eaves to ridge on opposite sides of the car, said roof sheets having inverted U-shaped flanges at their side margins lapped to form seams, the eaves end 85 of the outside flange being turned over the end of the adjacent inner flange to form a hood, said roof sheets having upstanding flanges at their ridge margins, ridge caps spanning the ridge flanges of the sheets, and 90 clips located beneath said ridge cap and secured to the ridge of the car between the ridge flanges of the sheets at the corners thereof, said clips having upstanding side flanges hooked outwardly and downwardly 95 at the top to embrace the ridge corner portions of the upstanding flanges of the adjacent roof sheets for spacing and holding said sheets in position.

3. An outside metal car roof comprising 100 roof sheets extending from eaves to ridge on opposite sides of the car, said roof sheets having upstanding flanges at their ridge margins and being movably connected along their side margins, ridge caps spanning the 105 ridge flanges of the oppositely disposed roof sheets, clips located at the ridge of the car between the ridge flanges of the sheets at the corners thereof, said clips having inverted U-shaped side marginal flanges 110 adapted to fit over the ridge corner portions of the upstanding flanges of the adjacent roof sheets for holding said sheets in position, running board saddles straddling the side seams and the adjacent ends of said 115 ridge caps, and means for securing said running board saddles to the car, said means passing through said clips for holding said clips in position.

4. An outside metal car roof comprising 120 roof sheets extending from eaves to ridge on opposite sides of the car, said roof sheets having inverted U-shaped flanges at their side margins lapped to form seams, the eaves ends of the outside flange extending 125 beyond the eaves ends of the sheets and being turned over the adjacent inner flange to form a hood, said roof sheets having upstanding flanges at their ridge margins, ridge caps spanning the ridge flanges of 130

5 said sheets, said ridge caps having lateral
foot flanges adapted to bear on the sheets
at each side of the ridge and having up-
standing flanges at their ends, clips located
5 at the ridge of the car between the ridge
flanges of the sheets at the corners thereof,
said clips having upstanding side flanges
hooked outwardly and downwardly at the
top to embrace the ridge corner portions of
10 the upstanding flanges of the adjacent roof
sheets for holding said sheets in position,
and running board saddles straddling the
side seams and the adjacent ends of said
ridge caps, said running board saddles hav-
15 ing slots formed in their under sides adapt-
ed to receive the upstanding flanges of the
ridge caps, and means for securing said
running board saddles to the car, said means
extending through said clips for holding
20 said clips in position.

5. A car roof comprising an end sheet
loosely secured to the car at the eaves and
having its inner side margin connected to
the adjacent sheet, the outer side marginal
25 portion of said sheet projecting over the car
end and being bent downwardly and termin-
inating in an inwardly and upwardly hooked
portion.

6. A car roof comprising end sheets ex-
30 tending from eaves to ridge on opposite
sides of the car and having doubled-under
flanges at their eaves ends for movably se-
curing the sheets to the car, said sheets being
35 spaced apart at the ridge and being connect-
ed to the adjacent sheets by side seams, ridge
caps spanning the ridge margins of said end
sheets, the outer side marginal portions of
said sheets projecting over the car end and,
40 together with the doubled-under eaves
flanges of the sheets, being bent downwardly
and terminating in an inwardly and up-
wardly hooked portion.

7. A car roof comprising end sheets ex-
45 tending from eaves to ridge on opposite
sides of the car and having doubled-under
flanges at their eaves ends for movably se-
curing the sheets to the car, said sheets being
50 spaced apart at the ridge and being con-
nected to the adjacent sheets by side seams,
ridge caps spanning the ridge margins of
said end sheets, the outer side marginal por-
tions of said end sheets projecting over the
55 car end and, together with the doubled-un-
der eaves flanges of the sheets, being bent
downwardly and terminating in an in-
wardly and upwardly hooked portion, the
outer end of the endmost ridge cap being
60 bent down over the down-turned outer mar-
gins of said sheets, and clips having one end
secured to the car end, the free ends of said
clips having hooked portions adapted to
engage the hooked portions of said end
sheets for holding said sheets down on the
car.

65 8. A seam construction for flexible roofs

wherein the roof sheets are arranged trans-
versely of the car with their eaves ends
loosely secured to the top of the roof sub-
structure, said seam construction comprising
70 inverted U-shaped flanges at the side
margins of the sheets arranged to loosely
interlock to form seams, the inner flanges of
the seams stopping at the eaves end of the
sheet and the upper flanges projecting be-
75 yond the eaves margin of the sheet and be-
ing turned down over the under flange at
the eaves to form a hood.

9. A seam construction for flexible roofs
wherein the roof sheets are arranged trans-
versely of the car and have doubled-under
80 flanges at their eaves ends, eaves flashing
strips secured to the car and having por-
tions adapted to be hooked into the doubled-
under flange of said roof sheet for loosely
securing the eaves ends of said sheets to
85 the car, said seam construction comprising
flanges on one of the side margins of the
roof sheets turned upwardly and thence in-
wardly and downwardly and having flanges
90 on their opposite side margins turned up-
wardly and thence outwardly and down-
wardly and thence re-bent upwardly and in-
wardly, the upwardly and inwardly bent
flange at the side margin of one sheet slid-
ably engaging the upwardly and outwardly
95 bent flange of the adjacent sheet to form a
flexible seam, the inwardly bent flanges of
said sheet being cut back at an angle from
the doubled-under eaves ends of the sheets,
and the outwardly bent flange of said sheet
100 being arranged to project beyond the dou-
bled-under eaves end of the sheets and hav-
ing its end closed.

10. A roof sheet for a car roof, said roof
sheet having inverted U-shaped flanges at
105 each of its side margins, the U-shaped flange
at one side margin of said sheet terminat-
ing at the eaves end of the body portion of
the sheet, and the U-shaped flange at its op-
posite side margin projecting out beyond
110 the eaves end of the body portion of said
roof sheet and having its end turned down
in the form of a hood to close the same.

11. A roof sheet for a car roof, said roof
sheet having a flange at one of its side mar-
gins turned upwardly and thence bent in-
wardly and downwardly and having a simi-
lar flange at its ridge margin, the opposite
115 side margin of said roof sheet being turned
upwardly and thence outwardly and down-
wardly and thence re-bent upwardly and in-
wardly, the inwardly bent flange of said
sheet being cut back at an angle from the
eaves end of the sheet and the outwardly
120 bent flange at the opposite side margin of
said sheet being arranged to project beyond
the eaves end of said sheet and having its
end closed.

12. A roof sheet for a car roof having
doubled-under flanges at its eaves end for
125

- loosely securing the sheet to the car, said roof sheet having a flange at one of its side margins turned upwardly and thence bent inwardly and downwardly and having a 5 similar flange at its ridge margin, the opposite side margin of said roof sheet being turned upwardly and thence outwardly and downwardly and thence re-bent upwardly and inwardly, the inwardly bent flange of 10 said sheet being cut back at an angle from the eaves end of the sheet and the outwardly bent flange at the opposite side margin of said sheet being arranged to project beyond the eaves end of said sheet and having its top portion turned down at the end to form a hood.
13. An end sheet for a car roof, said sheet having a doubled-under flange at the eaves for loosely securing the sheet to the car, said 20 sheet having an inverted U-shaped flange at its inner side margin terminating at the eaves end of the sheets and adapted to loosely interlock with a similar flange of an adjacent sheet to form a flexible connection therewith, the outer side margin and the 25
- doubled-under eaves flanges of said sheet being bent down and thence re-bent inwardly and upwardly at an inclination to form a stiffening flange.
14. An end sheet for a car roof, said sheet 30 having a doubled-under flange at the eaves for loosely attaching said sheet to the car substructure, said roof sheet having an inverted U-shaped flange along its inner side margin adapted to interlock with a similar 35 flange of an adjacent sheet to form therewith a flexible seam, said end sheet flange projecting beyond the doubled-under eaves flange of said end sheet and having its top portion turned down to form a hood, the 40 outer side margin and the doubled-under eaves flange of said end sheet being bent down and thence re-bent inwardly and upwardly at an inclination to form a stiffening flange. 45

Signed at Parnassus, Pennsylvania, this 11th day of December, 1918.

WILLIAM A. BREWER,
GUSTAVE A. GRUENDLING.
